UNITED STATES PATENT OFFICE.

HAMILTON G. BLUMBERG, OF SAN ANTONIO, TEXAS, ASSIGNOR TO BLUMBERG MOTOR MANUFACTURING COMPANY, OF ORANGE, TEXAS, A CORPORATION OF TEXAS.

CYLINDER-HEAD.

1,282,531.

Specification of Letters Patent. Patented Oct. 22, 1918.

Application filed May 3, 1915. Serial No. 25,602.

To all whom it may concern:

Be it known that I, HAMILTON G. BLUMBERG, a citizen of the United States, residing at San Antonio, in the county of Bexar and State of Texas, have invented certain new and useful Improvements in Cylinder-Heads, of which the following is a specification.

This invention relates to an improvement 10 in removable cylinder heads for gas engines which can be applied to any number of cylinders, and the object is to provide integral intake and exhaust conduits. Water is received within the head for maintaining it 15 in a cool condition, and the water is caused to circulate around the intake and exhaust conduits and around the valve guides, so that all of the parts are maintained in a cool condition.

20 The invention relates to still other novel features of construction and combinations of parts which will be hereinafter more fully described and pointed out in the claims.

In the accompanying drawings:

25 Figure 1 is a longitudinal vertical sectional view;

Fig. 2 is a transverse vertical sectional view; and

Fig. 3 is a horizontal sectional view.

30 A represents the head, which is preferably made hollow for forming a water chamber through which the water may circulate for maintaining the head in a cool condition. I have only shown the head as being 35 applied to two cylinders, but it is not the intention to limit the application of the head to any particular number of cylinders. For each engine cylinder, as is well known, there is an exhaust and intake port, and in 40 this instance I have shown two exhausts and two intakes. The exhaust and intake conduits are cast integrally with the head, and the exhaust conduits are designated as 1, and the intake conduits as 2. The exhaust conduits are provided with a port which leads from one side of the casing through the 45 lower side thereof, as at 3, to the engine cylinder, through which the exhaust gases from the engine cylinder are discharged. The intake conduits 4, 4 are located adjacent to each other, and are so constructed that at their outer end they converge into a single conduit as at 5, each conduit 4 leading to an engine cylinder, while the conduit 5 leads to 55 the manifold, not shown. By this construction, a better distribution of the fuel is ob-

tained, than by the usual four-way method, generally provided.

The intake and exhaust ports, and particularly the exhaust ports 3, are formed 60 along the upper wall of the conduits 1 in an arc of say forty-five degrees. The purpose of this is to prevent the exhaust gases from carrying any gases, lubricating oil, carbon, or soot into the valve guides 6, which are 65 connected to the conduits and head, and extend above the head A for forming a guide for the valve stems 7, which carry the valves 8.

With the conduit or port generally provided in gas engines, the exhaust gases will 70 enter the guide along the valve stem, and eventually cause the stems to stick, but with the formation of the wall of the port at an angle of forty-five degrees at the point where 75 the valve stem slides into the guide, it is possible to overcome this objection, and prevent the direct influx of the gases into the valve guides. The intake ports are provided with a valve 9, which have stems 10 connected 80 thereto, sliding through guides 11, which are constructed similarly to the guide conduits and stem 7 of the exhaust stem 7 of the exhaust valves. These valves are seated against the lower side of the head for forming a 85 closure for the exhaust and intake ports, and are held in this position by means of the springs 12, 12.

The water jacket 13 around the engine cylinders B is in communication with the 90 chamber of the head A, so that a constant circulation of water is maintained. The inlet of the water is provided as at 14, in the water jacket of the cylinder, and the outlet port as at 15, of the head A. The head, 95 of course, is connected to the engine cylinder by means of bolts, 16.

I claim:

1. The combination with a cylinder head, of intake and exhaust conduits integrally 100 cast therein, valves for closing the conduits, valve stems connected to the valves extending through the head, said conduits having the upper walls thereof, where the valve stems pass through the head, formed in the 105 arc of a circle for causing the exhaust gases and foreign matter carried therewith to pass through the conduits without affecting the valve stems, the arched portion of said conduits extending beyond the point of entrance of said valve.

2. The combination with a removable hol-

low cylinder head, of integral conduits formed therein producing intake and exhaust ports, valves for closing the conduits, valve stems connected to the valves extending through the head, said conduits having the upper walls thereof, where the valve stems pass through the head, formed in the arc of a circle the axis of which is out of line with said valve stems for causing the ex-

haust gases and foreign matter carried there- 10 with to pass through the conduits without effecting the valve stem.

In testimony whereof I affix my signature, in the presence of two witnesses.

HAMILTON G. BLUMBERG.
